UNITED STATES PATENT OFFICE.

THEODORE A. SALA, OF DALLAS, TEXAS.

HEATER.

Application filed August 14, 1923. Serial No. 657,337

To all whom it may concern:

Be it known that I, THEODORE A. SALA, citizen of the United States of America, residing at Dallas, in the county of Dallas 5 and State of Texas, have invented certain new and useful Improvements in Heaters, of which the following is a specification.

This invention relates to new and useful improvements in heaters.

10 The object of the invention is to provide an improved heater particularly adapted to be used for fire places.

An important object of the invention is to provide a direct heat and an indirect 15 heat together with means whereby the direct heat may be delivered to the room or shut off therefrom and the fumes delivered to a flue.

Another object is to circulate the heat 20 currents in such a manner as to derive the greatest advantage therefrom.

A construction designed to carry out the invention will be hereinafter described together with other features of the invention.

25 The invention will be more readily understood from a reading of the following specification and by reference to the accompanying drawings, in which an example of the invention is shown, and wherein:

30 Fig. 1 is a front elevation of a heater constructed in accordance with my invention,

Fig. 2 is a longitudinal vertical sectional view of the heater,

Fig. 3 is an end elevation,

35 Fig. 4 is a transverse vertical sectional view taken on the line 4—4 of Fig. 2,

Fig. 5 is an enlarged detail of one of the end flues,

Fig. 6 is a plan view of a modified form, 40 and

Fig. 7 is a partial front elevation of the same.

In the drawings the numeral 10 designates a fire chamber having its front side 45 open. The fire chamber is surrounded on each side and back by a vertical air chamber or flue 11. The front of the air chamber is covered by an arched grille 12. The fire chamber has a converging top 13

50 merged at each side into diverging ducts or pipes 14. The top 13 has its front edge secured to the lower edge of the lintel of the arch and admits air above said top. The vertical legs or sides of the grille admit air to the chamber 11 from which it passes up 55 and around the pipes 14 and mixed with

the air admitted above the top 13, as is evident from Fig. 4.

The pipes 14 are inclined upwardly, but have their ends directed horizontally to slip 60 into the lower collars 15 of vertical end flues 16. An upper cross chamber 17 surrounds the chamber 11 and the elements 13, 14 and 16 are disposed in the chamber 17. The rear walls of the chambers 11 and 17 65 may be continuous.

The end flues are smaller than the transverse area of the chamber 17. The front plate 18 of each flue forms the closure for the end of the chamber 17 and these plates 70 are exposed on the sides of the chimney or pilaster into which the chambers are set and in which they are concealed.

Each end flue has an upper collar 19 and these collars are connected by a cross pipe 20. The pipes 14 and 20 are large enough 75 to carry the heat currents and fumes from a suitable fire (not shown) in the chamber 10. The pipe 20 is spaced above the pipes 14 and is supported by foraminous standards 80 21 secured between the pipes. A flue 22 leads from the center of the pipe 20 and may be suitably connected with the chimney flue or other outlet. The currents from the fire chamber may be conducted directly 85 through the pipes 14, flues 16, pipe 20 and flue 22.

Louver slats 23 are pivoted in the plates 18 in the upper and lower sections and when opened deliver the heat currents from 90 the chamber 10 directly into the room in which the plates are exposed. Inclined ducts 24 arranged in staggered relation (Fig. 3) extend through the end flues between the lower sections and thus the indirect heat currents provided by the air entering the chamber 11 and circulating around the pipes 14 and 20 in the chamber 17, are delivered through the said ducts to 95 the room.

100 It will be seen that the heater may be installed in a chimney or a pilaster may be built in a room which does not have a flue. Only the grille 12 will be exposed on the front and the plates 18 on the sides. A suitable 105 gas, wood, coal or other fire may be provided in the chamber 10, the gas only being usable where there is no chimney flue.

The air from the various rooms is drawn in through the grille 12 into the chamber 11 110 and is warmed by indirect heat from the fire. The heated air currents from the chamber

11 pass up into the chamber 17. Air also enters the chamber 10 and is directly heated by the fire. The air from the chamber passes into the top 13 and is delivered into the pipes 14 from which it passes into the end flues 16.

If the lower slats 23 are closed the heat currents and fumes from the fire will pass up the flues around the ducts 24 and into the 10 pipe 20, from which they escape through the flue 22.

If the slats 23 are opened or partially opened, some of the heat currents will pass out into the room. The direct heat currents 15 passing through the pipes 14 and 20 and the parts 13 and 16 will heat the indirect air currents passing through the chamber 17 and escaping through the ducts 24. The chamber 17 will act to cause a heat radiation from 20 the parts 13, 14, 16 and 20 and thus obviate overheating.

As a precautionary means a flue 25 may be led out of the pipe 20 through the top of the chamber 17, instead of the flue 22, as is 25 shown in Figs. 6 and 7. In chamber 17 a perforated collar 26 surrounds the flue 25 and permits a passage of air for cooling the flue.

Various changes in the arrangement and structure of the different elements as well as 30 modifications and alterations, may be made within the scope of the appended claims.

What I claim, is:

1. In a heating device, a fire chamber, an air admitting chamber contiguous to the fire chamber, a cross air chamber above the air chamber and connected therewith, conductors for the currents from the fire chamber passing through the cross chamber, and means for delivering the heated air from the 40 cross chamber.

2. In a heating device, a fire chamber, an air admitting chamber contiguous to the fire chamber, a cross air chamber above the air chamber and connected therewith, conductors for the currents from the fire chamber 45 passing through the cross chamber, and end flues connected with the conductors, and means for passing the air currents from the cross chamber through the end flues and delivering them.

3. In a heating device, a fire chamber, an air admitting chamber contiguous to the fire chamber, a cross air chamber above the air chamber and connected therewith, conductors for the currents from the fire chamber 55 passing through the cross chamber, means for delivering the heated air from the cross chamber, and means for delivering into the room a portion of the currents passing 60 through the conductors.

4. In a heating device, a fire chamber, an air admitting chamber contiguous to the fire chamber, a cross air chamber above the air chamber and connected therewith, conductors for the currents from the fire chamber 65 passing through the cross chamber, end flues connected with the conductors, and means for passing the air currents from the cross chamber through the end flues and delivering them, and means for delivering into the room a portion of the currents passing from the conductors through the end flues.

5. In a heating device, a fire box for directly heating air current, a surrounding chamber for indirectly heating air currents, 75 a heating chamber receiving the indirectly heated air currents, end flues receiving the directly heated currents, a means for conducting the directly heated air currents from the end flues, means in the end flues for discharging a portion of the directly heated air currents therefrom into the room, and means for conducting the indirectly heated air currents, from the heating chamber through the end flues and delivering the same into the 85 room.

6. In a heating device, a fire chamber having an open front, an air chamber surrounding the fire chamber on three sides, a grille covering the front of the air chamber, a laterally extending heating chamber into which the air chamber discharges air conductors diverging from the top of the fire chamber, end flues at the ends of the heating chamber connected with the conductors in the heating 95 chamber, means for conducting currents from the end flues to a chimney flue, means for optionally discharging air currents from the end flues into the room, and means for conducting air currents from the heating 100 chamber through the end flues.

7. In a heating device, a fire chamber having an open front, an air chamber surrounding the fire chamber on three sides, a grille covering the front of the air chamber, a laterally extending heating chamber into which the air chamber discharges air conductors diverging from the top of the fire chamber, end flues at the ends of the heating chamber connected with the conductors in the heating 105 chamber, plates closing the ends of the heating chamber and the end flues, a cross connecting pipe extending between the end flues in the heating chamber and having a flue outlet, louvers in the end plates, and ducts passing through the end plates and the end flues from the heating chamber.

In testimony whereof I affix my signature.

THEODORE A. SALA.
